UNITED STATES PATENT OFFICE.

SAMUEL D. MOTT, OF PASSAIC, NEW JERSEY.

WATER CIRCULATION FOR BOILERS.

SPECIFICATION forming part of Letters Patent No. 686,527, dated November 12, 1901.

Application filed June 1, 1901. Serial No. 62,810. (No model.)

To all whom it may concern:

Be it known that I, SAMUEL D. MOTT, of Passaic, Passaic county, New Jersey, have invented certain new and useful Improvements 5 in Water Circulation for Boilers, of which the following is a full, clear, and exact description.

My invention relates to improvements in water circulation for boilers, and more particularly steam-boilers.

My invention is also especially adapted for use in connection with that class of water-tube boilers in which a header is used for containing the water-supply and from which the 15 water is forced into the tubes.

The objects of my invention are to produce a simple internal circulatory system by which the water can be forced very rapidly into and through the water tubes or coils, to produce 20 a structure of this kind which is simple and economical, to produce an apparatus which can be driven from mechanism outside the boiler, so that the desired speed of circulation can be easily controlled, and, in general, 25 to produce a circulation system which will hasten steam production, and so lessen the cost of steam.

To these ends my invention consists of certain features of construction and combinations of parts, which will be hereinafter described and claimed.

Reference is to be had to the accompanying drawings, forming part of this specification, in which similar figures of reference refer to 35 similar parts throughout the several views.

Figure 1 is a vertical longitudinal section of a boiler-header provided with my improved circulatory device. Fig. 2 is an end elevation of the header and the driving means for 40 moving the circulatory apparatus, the view also showing means for driving an external water-feed to supply the boiler. Fig. 3 is a plan view, partly in section, of the device illustrated in Figs. 1 and 2; and Fig. 4 is a 45 detail sectional plan of the driving mechanism and the internal arrangement of pistons in the header.

I have shown my invention in connection with a header 10 of the kind illustrated in an 50 application for Letters Patent of mine, serially numbered 38,701, filed December 4, 1900; but my invention can be used with other types of

header. As illustrated, the header or drum 10 is cut away on the back, as shown at 11, to provide space for boiler-tubes, and it is also 55 provided with a water-feed 12, having boiler connections 13 and 14. These have nothing to do with my present invention and are shown merely to make the device complete. The type of header illustrated has tube connections 10^a and 10^b at top and bottom, as shown clearly in Fig. 3; but the arrangement of tubes is not material. It will be understood, however, that whatever the tube arrangement may be the outflow will be from 60 the water-holding part of the header and the return will be through the upper connection 10^a, this being as usual in all boilers of this type.

The header is divided below the water-line 65 by a horizontal partition 27, which merges into an internal casing 28. (Best shown in Figs. 2 and 3.) This casing has openings 29 and 30 at top and bottom, so that the water may circulate through it from the top down, 70 as indicated by the arrows in Fig. 3.

Within the casing 28 is a pair of pistons 31, of irregular oblong formation, the parts of which mesh, as the drawings clearly show, and thus when the two pistons are turned in 80 unison they serve the purpose of a rotary-piston pump and force the water from above the partition 27 downward through the opening 30 and out through the tubes connected with the header. These tubes are not shown, because they form no part of the invention; but they return through the connections at the upper part of the header, so that the water forced out through the tubes comes back, either as steam or water, into the top portion 90 of the header, and as the pistons 31 extend entirely across the casing 28 they serve admirably the purpose of pumping, and the forced circulation is kept up. I do not limit my invention to the particular form of internal pump shown, although this is well adapted for the purpose.

It is obvious that various mechanical means can be employed for turning the pistons 31; but, as illustrated, they are secured to shafts 100 32, which at one end are journaled within the header 10, as shown in Fig. 2, and extend outward through stuffing-boxes 32^a, being journaled on the outside in a bracket-

frame 33 on the front of the boiler. The two shafts are geared together by the meshing gear-wheels 34, (see Figs. 1 and 2,) and one of the shafts 32 has a gear 35, which may be driven from any suitable source of power, and of course any other means can be substituted for turning the shafts.

It will be seen that the arrangement described for forcing the circulation is well adapted for boilers employed in automobile-work, as the gear-wheel 35 or its equivalent may be turned from some running part of the vehicle, and so if the vehicle is running fast, and consequently using much steam, the circulation will be rapid and steaming made easy, while, on the other hand, as the speed lessens the circulation correspondingly lessens.

I have shown in the accompanying drawings mechanism for working the water-feed in the receptacle 12, because the said mechanism is used in connection with the internal boiler circulation.

One shaft 32 has a worm 36 thereon, which engages and drives a worm-wheel 37 on the vertical shaft 38, the latter being journaled in the bracket-frame 33, above referred to, and in a bracket 39 below it, and the shaft 38 carries a worm 40, meshing with and driving a worm-wheel 41 on the shaft 42, which is arranged below and at right angles to the shafts 32, being journaled in the bracket 39 and the bracket 43 on the boiler-front. The shaft 42 carries a cam-wheel 44, which engages the roller 45 on the slide-block 46, the latter being slidable vertically in the guide-way 47, which is supported on the bracket 48, as shown in Fig. 1. The slide-block 46 is rigid on the shaft 49, which extends upward through a stuffing-box 50 into the receptacle 12 and operates the valve mechanism (not shown) in the tank for regulating the water-feed to the boiler.

Referring to Fig. 3, it will be noticed that the essential thing is to have the boiler or header divided below the water-line at a point between the outgoing and incoming tubes and that the pump be located in the opening through the partition, so that when started it will force the water outward through the tube connections.

In the header 10 of the boiler I have shown a low-water alarm or indicator, which, how-

ever, has nothing to do with my present invention. This indicator comprises a float 56, 55 a bent arm 57, secured to the float, a shaft 58, extending outward through a stuffing-box in the header-front, a crank-arm 59 on the shaft, and the usual cord 60. I refer to these parts as they are shown in the drawings; but 60 the header can be used with or without them, as desired.

Having thus described my invention, what I claim as new, and desire to secure by Letters Patent, is—

1. The combination with a divided boiler having outflow and return connections for tubes on opposite sides of the division, of a pump or water-forcing device located in the division and adapted to force the water out 70 through the outflow connections.

2. The combination with a divided boiler having outflow and return connections for tubes on opposite sides of the division, of a connection between the two boiler-compartments whereby water may flow from one part to the other, and an internal pump or water-forcing device arranged to force the water through the outflow connections.

3. The combination with a boiler divided 80 below the water-line, of a rotary pump located in the said division and adapted to draw the water from one part and force it through the other.

4. The combination with a boiler divided 85 below the water-line and with an internal casing opening into the two divisions, of a rotary pump located in the said casing.

5. The combination with a boiler divided below the water-line, of a casing forming a 90 part of the said division but opening into the two compartments, and rotary meshing pistons turning in the casing.

6. The combination with a boiler divided below the water-line and with a casing forming 95 a part of said division, said casing opening into both compartments, of a rotary-piston pump contained in the casing, and means outside the boiler for driving the said pump.

In testimony whereof I have signed my 100 name to this specification in the presence of two subscribing witnesses.

SAMUEL D. MOTT.
